England

Application July 15, 1952, Serial No. 298,896

4 Claims. (Cl. 230—175)

This invention relates to footpumps, and in particular to footpumps for inflating pneumatic tires, especially of road vehicles.

For use in the inflation of pneumatic tires, footpumps are generally preferable to handpumps as being easier and less tiring to operate. However, footpumps have the disadvantage that they are heavier and occupy more space in storage than do handpumps and consequently it is difficult to carry footpumps on road vehicles, particularly on motor cycles, having only a limited space for the storage of tools and equipment. Similar considerations apply in the case of light aircraft, where storage space and the load which can be carried are relatively limited.

It is an object of the said invention to overcome this disadvantage.

According to the invention, a footpump is foldable so as to require when folded less storage space than when unfolded.

The said footpump may have a foldable base and a foldable operating lever which can unfold into operative positions when it is desired to use the pump.

The said foldable base may be in two parts pivotally connected together and capable of forming the pump support or foot when unfolded.

The said foldable operating lever may be in two portions pivotally connected together, the one portion being foldable on to the other portion when reduction in the length of the said lever is desired for storage purposes.

One portion of the operating lever may be connected to one moving part of the pumping mechanism of the pump, for example the piston or pistons by a cross-member through which motion is transferred from the operating lever to the said moving part.

The said footpump may have a plurality of cylinders disposed in side-by-side relationship and shorter in length than the single cylinder of a footpump of conventional kind and similar capacity, whereby the amount of air displaced by pistons working in the said cylinders during a working stroke is comparable with that which would be displaced by a piston working in the said single cylinder of the said conventional kind of pump.

The said plurality of cylinders is preferably in communication with a single outlet which is adapted to have the usual flexible delivery pipe connected to it.

The said footpump may have a return spring which is carried on a rod accommodated in a housing separate from the cylinders.

The accompanying drawings illustrate a construction in accordance with the said invention. In the drawings:

Figure 1 is an elevation of a footpump in an operative position,

Figure 2 is an elevation of the said footpump in a folded position,

Figure 3 is a plan view of Figure 2, and

Figure 4 is an end view in section on line 4—4 of Figure 2.

Referring to the drawings, in the construction of foot-

2

pump shown therein for inflating the pneumatic tires of road vehicles, we provide a cylinder block 1 having two cylinders 2 confined side by side in parallel position by end plates 3 and 4 respectively which are secured to one another by rods 5 and nuts 6. The two cylinders 2 fit into grooves in the inner surfaces of the end plates 3 and 4 and form fluidtight joints with the plate 3 and are fitted with pistons 7 (see Figure 4) having piston rods 8 sliding in guide bosses 9 attached to the outer surface of the end plate 4. The end plate 3 has air passages 10 connecting the ends of the two cylinders 2 with a single air outlet 11 provided with a screwthreaded aperture 12 onto which the screwthreaded metal end of a flexible air delivery pipe (not shown) can be screwed to form a fluidtight joint. The end plates 3, 4 also have extending between them a housing 13 in which a rod 14 and a surrounding helical compression return spring 15 are slidably engageable, the axis of the housing 13 being parallel to the axes of the cylinders 2.

The cylinder block 1 is pivoted to a base framework 16 consisting of a pair of bars having two parts 17 and 18 respectively, connected together by transverse cylindrical rods 19, 20 respectively at their ends, the transverse rod 19 being pivotally mounted in a pair of lugs 21 attached to the end plate 3 of the cylinder block 1. The base framework 16 rests on the ground when the pump is in position for normal operation. The two parts 17 and 18 of each bar are pivotally connected to one another by rivets 21' at or about midway along its length, there being on the part 17 a projecting lug 22 for preventing pivotal movement of the part 18 about it in one direction beyond a predetermined amount. The part 17, to which the cylinder block 1 is pivoted, is somewhat longer than the cylinder block 1. The base framework 16 has an operating lever 23 pivotally connected to the rod 20 thereof at that end thereof remote from the end to which the cylinder block 1 is pivotally connected. The operating lever 23 is in two portions 24 and 25, the portion 24 having two metal bars two ends of which serve to pivot the operating lever 23 to the base framework 16 and which are pivotally connected to the portion 25 by rivets 26 at the other two ends. A transverse cylindrical rod 27 at the ends of the portion 25 of the operating lever 23 serves to pivotally connect the operating lever 23 to the piston rods 8 and return spring rod 14, the cylindrical rod 27 also serving to prevent the portion 25 from being turned in one direction about the pivot beyond a predetermined extent by impingement of the portion 24 against the rod 27. The cylindrical rod 27 has pivotally mounted on it a block 28 mounted on the end of each piston rod 8 and a block 29 mounted on the end of the return spring rod 14.

The portion 25 of the operating lever has two bars which are connected together at that end of the portion 25 which is remote from the rod 27 by a foot plate 30 which is pivotally connected thereto. On pushing down the plate 30 of the operating lever 23 with the foot the piston rods 8 and pistons 7 are driven into the cylinders 2 and the return spring rod 14 and spring 15 are driven into their housing 13 by the operating lever 23. The movement of the pistons 7 causes displacement of the air in both cylinders 2, the air being driven out of the cylinders and through the air passages 10 and the outlet 11. Releasing the pressure of the foot on the plate 30 of the operating lever 23 allows the return spring 15 to urge the operating lever 23 upwards and away from the cylinder block 1 and the operating lever 23 draws the piston rods 8 and pistons 7 along the cylinders 2 until the pistons 7 have returned to the initial positions.

The footpump can be folded for storage or transportation by folding the two parts 17 and 18 of the base framework 16 together until the part 17 abuts against stops 31 projecting from the end plate 4, pushing the

operating lever 23 to drive the pistons 7 home whilst keeping the part 17 against the stops 31 and then folding the two portions 24 and 25 of the operating lever 23 and the two parts 17 and 18 of the base framework 16 completely together until the axis of the transverse rod 29 of the base framework 16 arrives at and then passes beyond the plane containing the axis of the transverse rod 19 and the axis of the transverse rod 27 and thereby exerting a toggle action serving to retain the footpump in its folded position against the action of the return spring 15. Each of the two bars of the part 18 of the base framework 16 has a lug 32 which engages the adjacent bar of the portion 24 of the operating lever 23 when the pump is in its folded position and serves to prevent movement of the parts beyond the desired folded position by the return spring 15. The footplate 30 of the operating lever 23 is folded flatly against the bars of the operating lever and base framework, as shown in Figures 2, 3 and 4, and forms a flat end of the folded structure which is helpful when stowing and handling. The footpump now occupies between about one half and two thirds of the length which it occupied in its unfolded condition, and is in a flat and compact form for easy stowage in a confined space.

The piston rods 8 and return spring 15 and rod 14 are totally enclosed when the pump is folded and thereby dirt and grit are excluded from these parts. The use of two short cylinders instead of one long one makes it possible to use smaller gauge bars for the base framework and operating lever and thereby makes the footpump lighter than a similar one of conventional kind.

We claim:

1. A footpump having a base framework, an operating lever, a plurality of cylinders, pistons working in the said cylinders, piston rods provided on said pistons, a cross piece, two parts pivotally connected together for forming the said base framework and swingable downwards only on each other into a folded state, and two portions pivotally connected together for forming the said operating lever and being foldable on each other, one part of the base framework having a pivotal connection to said cylinders, the other part having a pivotal connection to one portion of said operating lever, said cross piece being fixable to said piston rods, and the other of said portions of the operating lever having a pivotal connection to said cross piece as well as to said first-named portion.

2. A footpump having a base framework, an operating lever, a pair of cylinders, pistons working in the said cylinders, piston rods provided on said pistons, a cross piece fixed to said piston rods, a rod also fixed to said cross piece, a casing fixed to said cylinders parallel and adjacent thereto and engageable with clearance by said rod, a return compression spring on said rod and accommodatable in said casing, two parts pivotally connected together for forming the said base framework and swingable downwards only on each other into a folded state, and two portions pivotally connected together for forming the said operating lever and being foldable on each other, one part of the base framework having a pivotal connection to said cylinders, the other part having a pivotal connection to one portion of said operating lever, the other of said portions of the operating lever having a pivotal connection to said cross piece as well as to said first-named portion, said rod with spring and said casing serving for urging said cross piece and therefore said piston rods outwardly from said cylinders and also for returning said operating lever after operation of the same in a pumping direction.

3. A footpump having a base framework, an operating lever, a pair of cylinders having a common outlet, pistons working in said cylinders, one-way valve means incorporated with said pistons, said cylinders being connected for independent operation for pumping through said common outlet air fed directly and separately to each

cylinder, piston rods provided on said pistons, a cross piece fixed to said piston rods, a rod also fixed to said cross piece, a casing fixed to said cylinders parallel and adjacent thereto and engageable with clearance by said rod, a return compression spring on said rod and accommodatable in said casing, two parts pivotally connected together forming the said base framework and swingable downwards only on each other into a folded state, and two portions pivotally connected together for forming the said operating lever and being foldable on each other, one part of the base framework having a pivotal connection to said cylinders, the other part having a pivotal connection to one portion of said operating lever, the other of said portions of the operating lever having a pivotal connection to said cross piece as well as to said first-named portion, said rod with spring and said casing serving for urging said cross piece and therefore said piston rods outwardly from said cylinders and also for returning said operating lever after operation of the same in a pumping direction, stop means for preventing said base framework being swingable in a direction other than downwards, and further stop means for preventing said base framework from being swingable beyond a position in which said parts of said base framework are in said folded state, said cross piece further serving for preventing said portions of said operating lever from folding on each other when foot pressure is applied to the non-connected end of the second-named portion of said operating lever.

4. A footpump having a base framework, an operating lever, a pair of cylinders disposed side-by-side and having a common outlet, said cylinders being less in length than half that of said base framework, pistons working in said cylinders, one-way valve means incorporated with said pistons, said cylinders being connected for independent operation for pumping through said common outlet air fed directly and separately to each cylinder, piston rods provided on said pistons, a cross piece fixed to said piston rods, a rod also fixed to said cross piece, a casing fixed to said cylinders parallel and adjacent thereto and engageable with clearance by said rod, a return compression spring on said rod and accommodatable in said casing, two parts pivotally connected together for forming the said base framework and swingable downwards only on each other into a folded state, and two portions pivotally connected together for forming the said operating lever and being foldable on each other, one part of the base framework having a pivotal connection to said cylinders, the other part having a pivotal connection to one portion of said operating lever, the other of said portions of the operating lever having a pivotal connection to said cross piece as well as to said first-named portion, said rod with spring and said casing serving for urging said cross piece and therefore said piston rods outwardly from said cylinders and also for returning said operating lever after operation of the same in a pumping direction, stop means for preventing said base framework from being swingable in a direction other than downwards, and further stop means for preventing said base framework from being swingable beyond a position in which said parts of said base framework are in said folded state, said cross piece further serving for preventing said portions of said operating lever from folding on each other when foot pressure is applied to the non-connected end of the second-named portion of said operating lever, said footpump being foldable and thereby reducible to substantially half its length compared with that when unfolded for operation, on folding the parts of the base framework downwardly, pushing the piston rods into said cylinders against said spring, and folding said second-named portion of the operating lever about its pivotal connection to said first-named portion until both portions of the operating lever lie adjacent said parts of said base framework, the relative positions of the components of the footpump being such that a toggle action is exerted which

serves for keeping the footpump in its folded state against
accidental and unintentional unfolding.
